JACK

Earl G. Gunn, Racine, Wis.

Application August 5, 1939, Serial No. 283,488

19 Claims. (Cl. 254—106)

My invention relates in general to improvements in jacks of the type in which the load-carrying element is frictionally held against movement relative to the supporting element with respect to which it is adjusted.

More specifically my invention relates to jacks of the type as disclosed in my copending application, Serial No. 246,048, filed December 16, 1938, and covers various improvements over and 10 in addition to the structure disclosed in said application.

An important object of my invention is to provide jacks of the type referred to with a housing structure which substantially encloses the 15 working parts thereof for protection and at the same time serves to perform operative functions with such parts when the jack is in operation.

Other and further objects of the invention will become apparent to those skilled in the art from 20 the following detailed description of the annexed drawings, which disclose two embodiments of my invention.

On the drawings:

Figure 1 is a vertical section, with parts in elevation, of a jack structure according to my invention with parts arranged for lifting or load-elevational purposes.

Figure 2 is a vertical sectional view similar to Fig. 1, with parts in fragmentary elevation, disclosing the arrangement of parts for releasing or load-lowering purposes.

Figure 3 is a horizontal sectional view taken substantially along the line III—III of Fig. 1.

Figure 4 is a fragmentary elevational view of 35 the lower portion of the jack housing as disclosed in Fig. 1, showing the reversible locking means which determines the arrangement of parts for load-elevational or load-lowering purposes.

Figure 5 is a view similar to Fig. 1 but taken 40 from the opposite side, showing another embodiment of my invention.

Figure 6 is a vertical sectional view, with a part in fragmentary elevation, of the jack housing of Figure 5 as taken from the rear.

Figure 7 is a vertical sectional view similar to 45 Fig. 5, with parts in fragmentary elevation, disclosing the arrangement of parts for releasing or load-lowering purposes.

Figure 8 is a horizontal sectional view taken 50 substantially along the line VIII—VIII of Fig. 5, with parts in elevation.

As shown on the drawings:

The reference numeral 10 designates generally 55 a jack according to this invention. This jack has a standard 11 upon which the operating housing

12 is mounted to move lengthwise. The standard 11 is in the form of a cylindrical rod supported by a base member 13 having a detent 14 in which the round end of the rod is seated.

The housing 12 is substantially cylindrical in 5 shape, as shown in Fig. 3, having side wall portions cut away to form openings 15 along the length thereof. At its upper end the housing is provided with a cap 16 of larger diameter than that of the housing. This cap 16 is secured to 10 the housing 11 by welding or other suitable means, or can be a bulged portion integral with the housing walls.

A portion of the side wall of cap 16 is pressed 15 outwardly to form a projecting peak 17 which projects outwardly above one of the openings 15. An integral end wall 18 of the housing is provided with an opening 19 through which the standard 11 is received.

A load-carrying member 20 is rotatably secured 20 to the cap 16 and is provided with an opening 21 as a bearing in the top end of the housing for the standard 11. This load-carrying member 20 is suitably shaped to engage and carry the 25 load to be raised or lowered.

The top end of the standard 11 has pinched ears 22 for limiting the raising of the load-carrying member 20. Limiting of the upward movement on the standard can also be effected by upsetting the top portion thereof as shown in Fig. 5. 30

A friction holding member comprises a pair of plates 23 having offset openings 24 through which the standard 11 extends. The long ends of the plates extend through one of the housing openings 15 to bear against the cap projecting peak 35 17. A shelf 25 is secured to the inside of and across the housing 12, by welding or other means, at a position adjacent the load-carrying end. A central opening 26 is provided in this shelf through which the standard extends freely. A 40 coil spring 27 seats on the shelf 25 and urges the friction holding plates 23 in an upward direction to cant the plates against the projecting peak 17.

The other or short ends of the plates 23 are 45 limited in an upward direction by a laterally extending lug 28 of a link 29. This link will be more fully described later.

The reference numeral 30 generally designates 50 a spring cage which comprises a U-shaped plate 31, best shown in Fig. 6. The inturned ends form shelves 32 and 33 and have aligned openings 34 therethrough for receiving the standard 11 freely. An upper coil spring 35 seats against the 55

upper shelf 32 and a lower coil spring 36 seats against the lower shelf 33.

A flat vertically offset extension 37 projects outwardly from the lower shelf 33 through the wider opening 15, as clearly shown in Fig. 3. At two points adjacent the bottom end of the housing 12 slots 38 and 39 are provided, as shown in Fig. 4. The lower slot 39 has a downward projection 40 while the upper slot has an upward projection 41, the latter being shown in locked position in Fig. 4. An opening 42, larger than the projections 40 and 41, is provided at one side of the extension 37 for locking the extension with the housing 12 at the predetermined points 38 and 39. By disengaging the extension 37 from either of the slots 38 or 39, the spring cage is capable of being moved longitudinally along the standard 11 within the housing 12 by operating the extension plate manually. While this method 20 only of locking the spring cage with the housing is shown in the drawings, other methods such as inclined slots in the housing or detents in the extension plate can be used equally as well. Once the two parts are seated the springs in the cage 25 provide the necessary tension or compression to hold them in engagement.

Referring again to Fig. 1, a friction control member comprises a pair of plates 43 having central openings 44 through which the standard 11 extends. Normally these plates are held in a floating position on the standard in transverse relation to the axis thereof by the cage springs 35 and 36. A U-shaped housing 45 surrounds the standard and encompasses the plates 43 lengthwise thereof. This housing 45 extends through the openings 15 in the housing walls and is provided at its free end with a transverse opening 46. An operating lever socket 47 is pivotally connected to the housing 45 at the opening 46 by a bolt or rivet 48. The lever socket 47 is also provided with an opening 49 through which a bolt or rivet 50 pivotally supports the link 29 adjacent the pivot 48.

The link 29 extends upwardly into engagement 45 between the slot 51 and the cap 16. The laterally extending lug 28 of the link 29 bears upon the upper side of the top plate 23.

The parts of Fig. 1 are so arranged that the operation of the lever socket 47 causes the jack 50 to operate upwardly or in a load-elevational direction. To operate in this direction, the spring cage 30 is manually lifted to engage and lock in the slot 38. By so doing, the lower spring 36 urges the plates 43 upwardly. The link 29 limits the vertical movement of the ends of plates 43 adjacent thereto so that the opposite ends are urged upwardly to a point in which the plates assume a canted position. This canted direction is such that downward pressure on the plates 43 60 may be exerted without changing their position relative to the standard against which they frictionally grip.

Power for lifting a load, carried by the member 20, is applied through the link 29 by a lever (not shown) which is inserted in the lever socket 47. With the lever fulcrumed at the stationary pivot 48, an upward swinging movement thereof causes the link 29 to lift the cap 16 together with the load-carrying member and the load (not shown). As the cap and its depending housing 12 move upwardly, the lower spring 36 is contracted by the locked shelf 33 moving with the housing. As soon as the lifting force is relieved by swinging the operating lever downwardly, the contracted 75 spring 36 expands to its full length and moves

the control plates 43 vertically. During this movement the load is carried by the holding plates 23 which are canted to prevent downward, but not upward, movement. By swinging the operating lever upwardly and downwardly the 5 load may gradually be raised.

In this manner the load is alternately carried by the friction members and results in a step-by-step upward or load-elevating movement.

In accordance with my invention, I provide 10 means for reversing the movement of the load without affecting its raised position. This is shown in Fig. 2. While the raised load is held in position by the holding plates 23, the extension plate 37 is released from its locked position in 15 the slot 38 and the spring cage lowered to a position in which it is again locked in the slot 39. Compression of the spring 35 holds the plate 37 in locked relation between the opening 42 and the downward projection 40 of the housing 12. 20 As the movement of the ends of control plates 43, adjacent the link 29, are limited in a downward direction the spring 35 urges the control plates to assume a canted position opposite that of the position in Fig. 1. This canted direction is such 25 that upward pressure on the control plates 43 may be exerted without changing their position relative to the standard against which they frictionally grip.

With the operating lever fulcrumed at the stationary pivot 48, a downward swinging movement thereof causes the lug 28 of the link 29 to bear upon the raised ends of the canted holding plates 23. By releasing the friction of these plates against the standard the load is dropped with 30 the downward swinging of the operating lever. As soon as the lever swings as far downwardly as the operator desires, a reversing of the swing of this lever upwardly releases pressure on the plates 23 by the lug 28. The spring 27 then cant 40 the holding plates in a direction to hold the load stationary. The movement in a downward direction of the load-carrying housing 12 compresses the spring 35. By transferring the load from the control plates 43 to the holding plate 45 23, the compressed spring 35 expands to its full length to move the control plates downwardly.

In this manner the load is again alternately carried by the friction members and results in a step-by-step load lowering movement. 50

It is to be noted that a full control of the load, when moved in either direction, is possible at all times and that the jack housing is an important part in the operating function of the jack.

Figs. 5 to 8 disclose another embodiment of 55 this invention. All of the parts of Figs. 5 to 8, which are identical with those in Figs. 1 to 4, carry the same reference numerals. All of the parts which are similar but not identical, carry the same reference numerals with the addition 60 of a subscript "a."

The reference numeral 16a generally designates the jack according to this embodiment. The cap 16a is provided with a projecting peak 17a which projects sufficiently outward to enclose the free 65 end of the link 29a. The standard has its free end 22a upset to limit vertical movement of the load-carrying member 20. A spring shelf 25a is disclosed as being secured within the housing 12 by projections 25b therethrough instead of welding as in the previous embodiment.

The embodiment disclosed in Figs. 5 to 8 is directed largely to the change in the operating lever mechanism. The U-shaped housing 45a is changed only with respect to its pivot ends 70 75

which extend sufficiently outward from the jack to allow for the operation of the link 29a in a more nearly vertical position. The housing 45a is provided with a pivot opening 46a to pivotally support the operating lever socket 47a by a bolt or rivet 48. As shown in Fig. 5, the socket 47a is shaped to receive a lever 52 for applying power to the jack.

The socket 47a is also provided at its end with a pivot opening 49a through which a countersunk rivet 50 (see Fig. 8) supports the lower end of the link 29a. The link 29a passes upwardly between the extensions of the U-shaped housing 45a and between the control plates 43 and the operating lever pivot 48. At its upper or free end, the link 29a is provided with an inwardly extending lug 28a which bears downwardly against the holding plates 23. The top of the link 29a bears upwardly against the cap 16a and is confined therein by the projecting peak 17a.

Operation of the jack in this embodiment is similar to that of the previous embodiment, except that the swinging operation of the operating lever 52 for either load-elevational or load-lowering purposes is reversed due to the reverse position of the link pivot 50 relative to the operating lever pivot 48.

Fig. 5 discloses the arrangement of parts for elevating a load by swinging the operating lever downwardly. Fig. 7 discloses the arrangement of parts for lowering the load by swinging the operating lever upwardly. Fig. 8 more clearly discloses the arrangement of parts of the operating lever mechanism.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a jack of the class described, the combination of a standard, a load-carrying member movable thereon, a holding member adapted to frictionally grip the standard when canted in one direction and resist downward movement of the load-carrying member thereon, a control lever mounted on the standard, means actuated by said control lever for canting said holding member in the reverse direction to release its grip upon the standard, and a housing secured to and depending from the load-carrying member and surrounding said standard, said holding member being releasably supported against said housing at the load-carrying end in a canted position and operated by said control lever.

2. In a jack of the class described, the combination of a standard, a frictional holding member and a frictional control member mounted on said standard and each adapted to grip the standard to hold said members against movement, a housing supported by the holding member and adapted at one end to support a load, said housing surrounding the standard and frictional members, an operating lever pivotally mounted on said control member, means operatively connecting said lever with the housing and holding member for moving the housing upwardly on said standard, said means being adapted to be actuated by said operating lever for releasing the holding member to lower said housing on the standard, and means for adjusting the control member to hold it against movement in either

direction depending upon the direction of movement of the load-carrying housing.

3. In a jack of the class described, the combination of a standard, a housing surrounding said standard and having one end adapted as a load-carrying member, upper and lower friction control members operatively associated with the housing and adapted to interlock with said standard when in relative angular position therewith, and reversible means associated with one of said control members for controlling both of them alternately for imparting a step-by-step movement to the housing in either direction.

4. In a jack of the class described, the combination of a standard, an operating housing, a load-carrying member secured at one end of said housing, said housing and load-carrying member movable on the standard, a holding member operatively associated with said housing and adapted to frictionally grip the standard to hold the housing against movement in a downward direction when the holding member is canted in one direction, an operating lever mechanism mounted on said standard within and operatively associated with said housing, and a link operated by said lever mechanism and operatively connected with the load-carrying end of said housing for raising the housing on the standard, said link adapted to cant the holding member in the reverse direction to release its gripping action on the standard and permit the housing to move downwardly thereon.

5. In a jack of the class described, the combination of a standard, a load-carrying member movable on said standard, a housing secured to and depending from the load-carrying member and surrounding the standard, a holding member adjacent the load-carrying end of said housing, an abutment supporting seat in said housing below the holding member, resilient means supported by said seat to urge said holding member against the end of said housing in a canted direction to frictionally grip the standard and hold the housing against movement in a downward direction, an operating cage having resilient means carried by said standard within the housing and movable longitudinally therein, said cage being adjusted in either direction exteriorly of said housing, a control member associated with said cage to normally float freely between the resilient means therein on the standard, said cage adjustment canting the control member to grip the standard thereby determining the direction of movement of the housing on the standard, an operating lever mechanism pivoted on said control member, and a link pivotally secured to said lever mechanism, said link being operatively associated with the load-carrying end of said housing for applying power thereto when acting in one direction and operatively associated with said holding member for releasing it when acting in the opposite direction.

6. In a jack of the class described, the combination of a standard, a load-carrying member movable on said standard, an elongated cap secured to and depending from the load-carrying member, a cylindrical housing secured to and depending from said cap, said housing having opposed wall openings along the length thereof, friction holding plates carried by the standard within the housing, a shelf extending transversely of the housing adjacent the load-carrying end thereof, a coil spring seated on said shelf to hold the holding plates against said cap in a canted direction to frictionally grip the standard and

hold the housing against downward movement, a movable operating cage carried by the standard confining a pair of springs between upper and lower shelves within said housing, said cage adapted to be adjusted in either direction exteriorly of said housing to a position in locked relation therewith to determine the direction of movement of the housing on the standard, friction control plates carried by the standard between the cage springs, an auxiliary housing encompassing the control plates, an operating lever pivoted on said auxiliary housing, a link pivotally secured to the operating lever having its free end confined between said cap and said holding plates, said cage adjustment canting the control plates about the axis of the lever pivot so as to grip the standard when the lever mechanism is operated whereby the link acts on the cap or holding plates depending upon the direction of movement of the housing.

7. In a jack of the class described, the combination of a standard, a load-carrying member movable on said standard, a housing secured to and depending from said load-carrying member, said housing having wall openings along the length thereof, a friction holding plate adjacent the load-carrying end of said housing, a transverse shelf secured within the housing, a spring between said shelf and holding plate to hold the latter in a canted position to frictionally grip the standard and hold the housing against downward movement, a movable operating cage carried by the standard within said housing and defining upper and lower shelves, said cage adapted to be adjusted in either direction to a position in locked engagement with the housing, upper and lower springs seated against said shelves, a friction control plate supported between the springs of said cage and adapted to be canted to frictionally grip the standard when the cage is adjusted to a locked position, an operating lever pivoted to the control plate, and a link pivoted to said operating lever to act upon said holding plate independently of the housing for releasing the holding plate when said cage is adjusted to a position in which the control plate is canted in a direction to grip the standard against upward movement thereof.

8. In a jack of the class described, the combination of a standard, a load-carrying member movable on said standard, a housing secured to and depending from said load-carrying member, said housing having wall openings along the length thereof, a friction holding plate adjacent the load-carrying end of said housing, a transverse shelf secured within the housing, a spring between said shelf and holding plate to hold the

latter in a canted position to frictionally grip the standard and hold the housing against downward movement, a movable operating cage carried by the standard within said housing and defining upper and lower shelves, said cage adapted to be adjusted in either direction to a position in locked engagement with the housing, upper and lower springs seated against said shelves, a friction control plate supported between the springs of said cage and adapted to be canted to frictionally grip the standard when the cage is adjusted to a locked position, an operating lever pivoted to the control plate, and a link pivoted to said operating lever to act upon said holding plate independently of the housing for releasing the holding plate when said cage is adjusted to a position in which the control plate is canted in a direction to grip the standard against upward movement thereof.

9. In a jack of the class described, the combination of a standard, a housing surrounding said standard and having one end adapted as a load-carrying member, said housing being movable on said standard, upper and lower friction control members operatively associated with the housing and adapted to interlock with said standard when in relative angular position therewith, and means associated with one of said control members for selectively canting said one member to determine the direction of movement of said housing on the standard.

10. In a jack of the class described, the combination of a standard, an operating housing, a load-carrying member secured at one end of said housing, said housing and load-carrying member movable on the standard, a holding member operatively associated with said housing and adapted to frictionally grip the standard to hold the housing against movement in a downward direction when the holding member is canted in one direction, a control member operatively associated with said housing and adapted to frictionally grip the standard when in canted relation therewith, an operating lever mechanism mounted on said control member and operatively connected to said housing and holding member, and means associated with said control member for selectively controlling the canted direction thereof whereby the operation of the lever mechanism moves said housing in one direction along the standard when the holding and control members are canted in the same direction and the housing moves along the standard in the opposite direction when said members are canted in opposite directions.

EARL G. GUNN.
